UNITED STATES PATENT OFFICE.

CHARLES S. WHEELWRIGHT, OF BRISTOL, RHODE ISLAND.

APPARATUS FOR COOKING GARBAGE OR OFFAL AND REMOVING THE OIL OR GREASE THEREFROM.

SPECIFICATION forming part of Letters Patent No. 774,804, dated November 15, 1904.

Application filed October 31, 1903. Serial No. 179,382. (No model.)

To all whom it may concern:

Be it known that I, CHARLES S. WHEELWRIGHT, of Bristol, in the State of Rhode Island, have invented a new and useful Improvement 5 in Apparatus for Cooking Garbage or Offal and Removing the Oil or Grease Therefrom, of which the following is a specification.

The main invention consists in the combination with a digester for cooking garbage of a trapped water and oil receiver located above said digester, the trap of said receiver consisting of the receiver itself and an operating leg or stand-pipe opening directly from said digester and extending upward in said receiver, whereby water and oil forced through said operating leg or stand-pipe may be caught in said receiver, and a valved pipe communicating with said receiver near the bottom outside of said trap, whereby water may be drawn off from beneath the oil.

The invention consists, further, in certain details of construction and in combinations of said details.

The process conducted by the apparatus herein described, like the process conducted by the apparatus described and claimed in my Patent No. 709,836, September 23, 1902, is a water process, the oil or grease of the garbage being taken up by water and conveyed 25 not after the cooking is substantially finished into a succession of separating-tanks, as in the said former apparatus, but continually during the cooking into a single separating-tank, located above the digester in which the garbage 30 is cooked, and there trapped to prevent the flow of oil and water back into the digester; nor, as in the said former apparatus, is the water accompanying the oil, or any of it, as it 35 passes into the separating tank or tanks received into the digester while the process of cooking goes on. In fact, the central heater of my former apparatus is in this apparatus omitted, and the garbage is cooked by steam entering the digester at the bottom and permeating the garbage throughout, fresh steam being admitted throughout the entire process 45 of cooking until the entire contents of the digester consist of the original boiling-water, water of condensation, and garbage, less water, grease, and oil, which have risen to the said

tank above, which now holds the said water, grease, and oil which have entered therein, permanently trapped or separated from the contents of the digester, the water and oil gage showing a marked line between the oil 55 and water in the said tank. The present digester has near the top a strainer or filter with large teats extending downward therefrom to prevent the clogging of the strainer by the garbage. There is also provided a valve 60 between the digester and the receiving-tank above, by which at the end of the cooking operation the contents of the tank, consisting of oil and water, may be shut off from the digester below. The drawing-off operations by 65 which the digester and the receiver are emptied of their contents are thus rendered independent of one another, a matter at times of great advantage.

In the drawing the apparatus is sufficiently 70 represented by a single figure, the same being for the most part a central vertical section.

A is the digester with conical ends built in sections, preferably of cast-iron, fastened together by bolts which pass through externally-projecting flanges, as shown at t. The interior walls of the perpendicular sections are coarsely corrugated, as shown. The upper conical section A' is truncated, as shown, 75 and ends in a filter-dome J, bolted to the said section, as shown at t', and having its own top bolted to the circular walls of the dome, as shown at t''. For the purposes of this invention the filter-dome may be regarded as a part 80 of the digester. At the junction of the digester and filter-dome, resting on the walls of the conical section A', is a filtering or clarifying bed or screen, consisting of two perforated plates a a', having the space between them filled with charcoal or other clarifying 85 substance a'', the whole contained between two other coarsely-perforated plates b b', the plate b being furnished with large teats c to keep the garbage from clogging the filter and resting on the walls of the conical section A', while 90 the plate b' rests on a ring d, which also serves to hold the plates a and a' and the charcoal in place. The plates b b' are of sufficient strength 95 and thickness not to be warped by the heat to which the digester and dome are subjected. 100

In some instances it will be sufficient to employ the plate *b* and teats *c* as a separator without the charcoal-filter, the necessary filter being provided in a trap, as hereinafter indicated. The dome *J* has at one side a large opening closed by a plate of proper shape, *J'*, which is held in place by a yoke and screw in the ordinary manner.

B is a receiving-tank formed in sections substantially in the same manner as the said digester and provided with a stand-pipe *C*, also formed in sections, which opening from the top of said digester extends from the bottom of said receiving-tank, within the same, to near the top thereof, as shown. The walls of the tank and of the stand-pipe should be of great strength. Between the digester and the receiving-tank is a valve-shell *D*, containing a valve (not shown) operated by a hand-wheel *W*, as indicated, by which communication between the digester and the receiving-tank may be shut off or regulated. A lower flange *d'* of the said valve-shell *D* is bolted to the digester, while to the upper flange *d* of said valve-shell the receiving-tank is bolted. Additional supports *e e*, &c., are furnished between the digester and receiving-tank. The lower part of the stand-pipe *C* is formed by the walls of the lower conical section of the receiving-tank, as shown at *f*, the remaining portion of the stand-pipe being bolted thereto at *f'*. The upper portion of the stand-pipe *C* contains a charcoal filter or clarifier *E*, secured to the top of the filter by hand-screws *g g*, as shown. The top of the receiving-tank *B* is removable, as shown, the opening closed by the said top being large enough for the removal of the charcoal-filter *E* from the apparatus to be cleaned or recharged with charcoal. The receiving-tank *B* is furnished with an oil and water gage *G*, as shown, connected to the said tank by pipes *F* and *F'*, as shown, and with a set of pipes *p' p*, &c., connecting with pipe *P*, by which oil may be drawn off from the tank *B* at various heights through valves *v' v*, &c., for storage. There are also a thermometer *H* and a pressure-gage *H'* connected to the tank by the said pipe *F*. Connected with pipe *F* also is an outlet-pipe *F''* for escaping gas, having a valve *V''*, which connects with a pipe *F''*, valved at *V''*, connecting with a condenser *M*, as shown. Connecting with pipe *F''* is a freshwater pipe *F'*, valved at *V'*. A continuation of the pipe *F'*, valved at *V'*, connects with pipe *F''* between the valves *V''* and *V'*, and between the same valves a pipe *F''*, valved at *V''*, leading from the top of the digester or from the top of the filter-dome *J*, connects with pipe *F''*. *T* is a pipe communicating with pipe *T'*, (valved at *V'*), leading to the boiler, and with pipe *T''*, (valved at *V''*), leading to the freshwater supply and ending in a circular pipe *T''*, which surrounds the lower conical section of the digester, as shown, the said circular pipe *T''* being provided with a number of pipes

T' T', &c., (but two are shown, although any number may be used,) passing through the wall of said conical section to the interior of the digester, where above the opening provided for each pipe *T'* is a deflector *K*, bolted to the interior wall of the digester, as shown, to direct the steam or water entering through the said pipes *T'* downward along the interior wall of the digester. The digester is provided with a large opening at *A* with a movable cover *A'*, which may be bolted, as shown, and a large exit at *X*, flush with the conical side walls of the digester, closed by a gate-valve *V'* in a pipe *Y*.

The operation is as follows: Valve *V''* is opened and a supply of water admitted to the digester sufficient to cushion the load of garbage which is dumped into the digester immediately upon the closing of the said valve *V''*. The cover *A'* is put on and fastened, and steam is admitted to the digester by opening valve *V'*, when the cooking commences and continues for seven or eight hours. The garbage contains about eighty per cent. of water, and this water, together with the cushion-water, increasing in volume by expansion under increase of temperature and by the addition of water from the condensation of the steam, carries upward, floating upon the surface, melted grease and oil extracted from the garbage through the filter and dome *J* into and through the stand-pipe *C* and the filter at the top of the stand-pipe, where water and oil flow over the receiving-tank *B*, the water falling to the bottom and the oil keeping on the top of the water. If the water of condensation supplied by the steam admitted through valve *V'* is not sufficient to keep up the necessary amount of water for increase of volume, as aforesaid, more water may be admitted from time to time by opening valve *V''*. At proper times water may be drawn off through pipe *F'* from the bottom of the receiving-tank and saved by opening valves *V''* and *V'*. So, too, as often as may be necessary water, oil, and steam may be blown off from the top of the digester or the filter-dome *J* through pipes *F''* and *F'* by opening valves *V''* and *V'*. At the conclusion of the cooking the valve *W* in shell *D* may be closed and the contents of the digester and receiving-tank separately dealt with. The rest of the operation is obvious.

Conforming to the present rules of the Patent Office requiring division between apparatus and method or process claims, I in this application make no claim to method or process, the same being fully claimed in a companion application filed herewith.

What I do claim as new and useful, and desire to secure by Letters Patent of the United States, is—

1. The combination with a digester for cooking garbage, of a trapped water and oil receiver located above said digester, the trap of said receiver consisting of the receiver itself

and an operating leg or stand-pipe opening directly from said digester and extending upward in said receiver, whereby water and oil forced through said operating leg or stand-pipe may be caught in said receiver, and a valved pipe communicating with said receiver near the bottom whereby water may be drawn off from beneath the oil, substantially as described.

2. The combination with a digester for cooking garbage, of a trapped water and oil receiver located above said digester, the trap of said receiver consisting of the receiver itself and an operating leg or stand-pipe opening directly from said digester and extending upward in said receiver, a valved water-pipe at the bottom of said receiver outside of said stand-pipe, and a valved oil-pipe communicating with said receiver above said water-pipe and outside of said stand-pipe, substantially as described.

3. The combination with a digester for cooking garbage, of a trapped water and oil receiver located above said digester, the trap of said receiver consisting of the receiver itself and an operating leg or stand-pipe opening directly from said digester and extending upward in said receiver, a valved water-pipe at the bottom of said receiver outside of said stand-pipe and a succession of valved oil-pipes above said water-pipe, whereby oil may be drawn off at different heights in said receiver, substantially as described.

4. The combination with a digester for cooking garbage provided with a strainer with large hanging teats across the upper portion thereof, of a trapped water and oil receiver located above said strainer, the trap of said receiver consisting of said receiver itself and a stand-pipe communicating directly with said digester above said strainer and extending upward within said receiver, substantially as described.

5. The combination with a digester for cooking garbage provided with a strainer with large hanging teats across the upper portion thereof, of a trapped water and oil receiver, the trap of said receiver consisting of said re-

ceiver itself and a stand-pipe communicating directly with said digester above said strainer and extending upward in said receiver, and a valved water-pipe near the bottom of said receiver outside of said stand-pipe, substantially as described.

6. The combination with a digester for cooking garbage provided with a strainer across the upper portion thereof, of a trapped water and oil receiver, the trap of said receiver consisting of the receiver itself and a stand-pipe communicating directly with said digester and extending upward in said receiver, the said stand-pipe being provided with a filtering apparatus at the top, substantially as described.

7. The combination with a digester for cooking garbage, of a trapped water and oil receiver, the trap of said water and oil receiver consisting of the receiver itself and a stand-pipe communicating directly with said digester and extending upward in said receiver whereby water and oil forced through said stand-pipe may be caught in said receiver, substantially as described.

8. The combination with a digester for cooking garbage, of a trapped water and oil receiver, the trap of said receiver consisting of the receiver itself and a stand-pipe communicating directly with said digester and extending upward into said receiver whereby water and oil forced through said stand-pipe may be caught in said receiver, and a valve whereby communication between said digester and said receiver may be closed, substantially as described.

9. The combination with a digester for cooking garbage having conical ends, of a steam-pipe encircling the lower conical end furnished with a number of pipes entering said lower conical end, of deflectors over each of said entering pipes to direct the flow of steam along the sides of the digester toward the bottom, substantially as described.
